Primary Examiner — Darlington Ly*Assistant Examiner* — Nasim Abdulaziz Ali(74) *Attorney, Agent, or Firm* — Troutman Pepper Hamilton Sanders LLP(57) **CLAIM**

The ornamental design for a front bumper, as shown and described.

DESCRIPTION

FIG. 1 is a top perspective view of a front bumper embodying my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a bottom perspective view thereof; and,

FIG. 9 is a front perspective view thereof.

The broken lines in the drawings illustrate portions of the front bumper that form no part of the claimed design.
